SHUTTER DEVICE FOR COUNTER
MECHANISMS

Einar M. Orbeck, West Hartford, Conn., assignor,
by mesne assignments, to Veeder-Root Incorporated,
Hartford, Conn., a corporation of Connecticut

Application July 23, 1941, Serial No. 403,629

5 Claims. (Cl. 235—1)

My invention relates to shutter warning means interconnected with an indicating registering mechanism for concealing the indicia wheels thereof from view from the initiation of the resetting-to-zero operation until such time as all of the counter wheels have been reset to their predetermined initial position. My invention is applicable to any register mechanism of the well-known types which include a plurality of indicia wheels and tens-transfer mechanism. Such register mechanisms are ordinarily connected to meters by which the volume of fluid dispensed is measured.

In many jurisdictions, mandatory regulations of the bureaus of weights and measures require that registering mechanisms, of types in which the indicia wheels are set forward to zero position, must be provided with means to conceal from view the indicia appearing upon the wheels during any resetting operation. Such requirements are for the protection of the buying public and are to prevent a dishonest operator either from initiating a subsequent dispensing operation until all of the counter wheels are first reset to zero position, or from advancing the counter wheels during resetting after a dispensing operation, to thereby dishonestly indicate to a customer that a greater amount of the commodity has been dispensed than actually has been measured.

My invention includes shutter means for covering the visible portions of the indicating wheels of a register to prevent a reading of the indicator when the register has not been reset to initial position, and means for moving such shutters out of concealing position to permit visibility of the indicia on the indicating wheels when the mechanism is being operated after a proper resetting of the indicator. If the registering means be fully reset to initial position prior to the initiation of a dispensing operation, the shutters means remain entirely out of view until such time as the register be subsequently reset to initial position.

It is an object of my invention to provide shutter means, interconnected with the resetting means of a register, which will automatically drop down and conceal the indicating wheels immediately upon any movement of the means utilized to effect a resetting-to-zero of the register.

Another object of my invention is to provide means to insure that the shutter means will remain in position to conceal the indicator wheels from view until such time as all of said indicator wheels have been completely returned to their initial position.

My invention includes the various novel features of construction and arrangement herein-after more definitely specified.

Fig. I is a partially vertical sectional view, taken on the lines I, I, in Fig. VIII, of my improved shutter mechanism embodied in a tens-transfer registering mechanism of the conventional type and enclosed within an outer casing, and showing such mechanism in its initial position after resetting to zero, in which position the shutter is raised to permit the indicator wheels to be visible through apertures in the wall of the outer casing.

Fig. II is a side elevation of the knee link by which the shutter means are raised and lowered.

Fig. III is an end elevation of the right hand side of the mechanism shown in Fig. II.

Fig. IV is a side elevation of the shutter operating mechanism shown in Fig. I and in the position which it assumes immediately upon the initiation of the resetting operation.

Fig. V is a side elevation of the shutter operating mechanism shown in Figs. I and IV and in the position which it assumes immediately following the position in Fig. IV, and in which the projection carried by one of the members of the knee link has been moved into the path of the knee link resetting stud carried by the reset cam, and with the cam roller moved from the cam notch to the periphery of the cam.

Fig. VI is a side elevation of the shutter operating mechanism shown in the position which it assumes after the knee link has been restored to straight line position.

Fig. VII is a side elevation of the shutter operating mechanism shown in the position which it assumes immediately prior to movement of the mechanism to raise the shutter to the position shown in Fig. I, and with the cam roller about to be engaged in the cam notch to compel the shutter to be moved to raised position.

Fig. VIII is a front elevation of the registry means shown in Fig. I, but with the outer casing removed and with the shutters in position to conceal the indicia appearing on the indicating wheels.

Referring to said drawings, the registering mechanism indicated is of the well-known conventional type including a plurality of indicia carrying wheels 1, provided with gear wheels 2 in engagement with conventional tens-transfer pinions 3. Said wheels 1 are mounted upon the shaft 4 conveniently journaled in the opposite bearings 4' which have reduced portions press-fitted respectively into the opposite side wall

members 5. Said registering mechanism is conveniently embodied in the housing 7 including the bottom closure 8, middle section 9, and top closure 10. Said middle section 9 is provided at the front thereof with a glass enclosed opening 12 permitting visibility of the indicia wheels 1 through a series of apertures 13 formed in the register means front cover plate 14 which is conveniently held in position by a series of screws 16 engaging the flanged brackets 17 connected to the side frame members 5.

Said registering mechanism includes the gear 20 adapted for engagement with the driving gear of any of the well-known types of fluid meters. Said gear 20 is conveniently fastened by means of the pin 21 to the shaft 22 which is journaled in the bottom closure 8. Said shaft 22 carries at its upper end the gear 23 rigidly secured thereon and in driving connection with the gear 25 mounted on the shaft 26 which is respectively journaled at its lower and upper ends in the closure plate 8 and cross-supporting member 27. Said member 27 is supported by the side frame members 5 and conveniently fastened thereto by means of a series of screws 28 in the downwardly turned flanges 29 of said cross member 27.

Said shaft 26 carries, intermediate of its length, the helical gear 30 fastened to said shaft 26, conveniently by means of the pin 31 in the hub 30' of said gear 30. Said gear 30 is in engagement with the gear 32 fastened to the shaft 33, the axis of which is at right angles to the axis of said shaft 26. Said shaft 33 is conveniently journaled in said side wall members 5. Said shaft 33 carries at its right hand end the gear 35 in engagement with the idle gear 36. Said gear 36 is conveniently mounted for freedom of turning movement on the stud shaft 37 mounted in the side wall bracket 5. Said gear 36 is in engagement with the gear 38 carried by the indicia wheel of lowest order, which is the wheel shown in Fig. I. Said shaft 33 is provided with a clutch of any of the well-known types to permit disengagement of the driving connection between the gear 32 and the gear 35 during the resetting operation of the counter.

The shutter 40 is comprised of a series of arcuate shutter fingers 42 of substantially the same width as the faces of the indicia wheels 1. When said shutter is in the upraised position as shown in Fig. I, the shutter fingers 42 do not obscure the indicia on the wheels 1 from appearing through the apertures 13 formed in the front plate 14. However, said shutter fingers 42 are of such length as to completely obscure from an observer the numbered wheels 1 through the apertures 13 when the shutter has been tripped and moved to its lowered position, as shown in Figs. IV to VIII inclusive. Said shutter 40 has the side arm members 43 and 44 provided with bearing surfaces 45 in engagement with the respective peripheries of the bearings 4', thereby permitting freedom of oscillatory movement for said shutter 40 and arcuate fingers 42 about the axis of the shaft 4.

Said side arm member 44 is provided with the enlargement 46 carrying the stud 47 rigidly mounted thereon. The tripping mechanism for the shutter includes the knee link comprising the upper member 48 and the lower member 55. Said upper member 48 is provided with the hole 49 and journaled for freedom of turning movement on the stud 47. Said link 48 carries, rigidly mounted thereon at its upper end, the tripping stud 52, the function of which is hereinafter described. Said link 48 is actuated with a snap

action by the over-center spring 47', one end of which is carried by and encircles the stud 47 and the opposite end of which is fastened to the stud 54 rigidly mounted in the right hand side frame member 5. The lower member 55 of the knee link is pivotally connected at its upper end by the rivet 56 to the upper knee link member 48. Said link member 55 is pivotally mounted at its lower end on the rivet stud 58 carried by the reset arm member 60 which is pivoted on the screw shaft 61 rigidly mounted in the side frame member 5. Said knee link members 48 and 55 are continually stressed toward the position shown in Fig. II by the spring 63, the opposite ends of which are connected respectively to the links 48 and 55. In such position, the three points comprising the axis of the resetting stud 52, the axis of the rivet pivot 56, and the axis of the pivot stud 58 are approximately in a straight line, said knee link member being over center only about $\frac{1}{2}$ of an inch. Said links 48 and 55 are prevented from assuming a position beyond that in which the aforesaid three points are approximately in a straight line by means of the upturned flange 55', formed at the upper end of the link 55, coming into engagement with the lower end of the link 48, as best shown in Fig. II.

Said shaft 4 has mounted at the right hand end thereof the cam 65 provided with the hub 66 having mounted in integral relation therewith the reset handle 67. Said cam 65 is provided with the cam notch 69 for engagement with the reset arm roller 70 which is mounted to turn freely on its rivet stud 71 rigidly mounted in said arm 60.

Said cam 65 has rigidly mounted thereon the stud 73 for engagement with the reset stud 52 of the knee link member when the cam 65 is in the position shown in Fig. VI. Said reset arm member 60 is continually stressed clockwise by the spring 75, one end of which encircles the stud 76 rigidly mounted on said reset arm member 60 and the other end of which spring encircles the screw stud 77 fastened to said side frame member 5.

Said shaft 61 extends through the side frame member 5 and carries at its opposite end a bifurcated spring-pressed brake shoe assembly, not shown, of ordinary construction, for engagement with the conventional type of clutch interposed between the gears 32 and 35 so that when the reset arm 60 is in the position shown in Figs. V to VIII inclusive, the train of gears including the gears 20, 23, 25, 30, and 32 remains stationary while said conventional type clutch permits freedom of movement of the gears 35, 36, 38, etc., during any resetting operation of the counter effected by a turning of the reset handle 67.

Said cam 65 carries the flat spring 80 which is rigidly connected at one end to said cam by the rivet 81. Said spring 80 has at its opposite end the tripping stud 82 which is adapted to extend through and slide freely in the circular bearing hole 83 formed in said cam 65. Said tripping stud 82 projects through said cam 65 to a sufficient extent to be presented in a plane wherein it may engage the tripping stud 52 carried by the upper member 48 of said knee link.

The resetting of the counter is effected by one complete revolution clockwise of the reset handle 67. As is well known and conventional in resetting counters of the type to which my invention is applicable, there is a continued over-throw movement of the resetting crank and cam 75 at the end of the resetting revolution to permit

and effect a proper lining up of the number wheels, following which the resetting cam and reset handle are then returned counterclockwise to a position represented by one complete revolution of the reset crank. In the structure herein shown, such counterclockwise compensating movement of the cam 65 is effected by the spring 75 when the roller 70 is seated in its final position in the cam notch 69, as shown in Fig. I. Therefore, I find it convenient to provide said stud 82 with an inclined cam face so as to permit said stud 82 to ride over the stud 52 counterclockwise from its overthrow position. Said stud 82 being mounted at the end of the flexible flat spring 80 and said stud 82 being free to move in the opening 83 formed in the cam 65, when the inclined cam surface of the stud 82 comes into engagement with the stud 52 during the counterclockwise movement of the cam 65 for compensation for the overthrow, the inclined surface of the stud 82 slides over the stud 52, which merely causes a flexing of the spring 80 which permits said stud 82 to be moved out of the path of the stud 52.

I also have found it convenient to provide a stop pawl 85 journaled on the stud 86 rigidly mounted in the side frame member 5. Said stop pawl 85 is continually stressed clockwise by means of a spring 87, one end of which engages the arcuate surface of said pawl 85, as shown in Fig. I, and the other end of said spring 87 encircles and is fastened to the stud 86. Once a resetting operation has been initiated, and the roller 70 moved out of the cam notch 69 by clockwise movement of the reset handle 67, any attempt to thereafter move the reset cam 65 in an improper counterclockwise direction would result in the stop pawl 85 engaging the cam notch 69 to prevent further counterclockwise rotation of said cam 65. During normal resetting operation in which the reset handle 67 and cam 65 are turned clockwise, said stop pawl 85 rides upon the periphery of the cam 65.

Operation

At the end of a measuring operation, the counter wheels have been advanced to a position indicating the quantity dispensed by the meter with which the gear wheel 20 of the registering mechanism is connected, and such quantity is indicated by the indicia on the counter wheels 1 visible to the observer through the apertures 13 formed in the cover plate 14. Fig. I also indicates the position of the mechanism at the end of a dispensing operation. To reset the register mechanism to zero position prior to the initiation of a subsequent dispensing operation, the operator turns the reset handle 67 clockwise one complete revolution plus the number of degrees represented by the amount of overthrow. Any initial clockwise resetting movement of the handle 67 causes the stud 82 to engage the stud 52 which is in its path, and any slight movement clockwise of the stud 52, and member 48 carrying said stud 52, permits the over-center spring 47' to overcome the forces exerted by the spring 63 and snap the knee link from the position shown in Fig. I to the position shown in Fig. IV. Continued clockwise turning movement of the reset handle 67 causes the cam roller 70 to move out of engagement with the cam notch 69 into engagement with the periphery of said cam 65, as shown in Fig. V. Movement of the cam roller 70 out of its cam notch 69 for engagement with the periphery of the cam 65 causes the member 55 of the knee

link, pivoted to said reset arm 60 carrying the cam roller, to move to the position shown in Fig. V and in which the stud 52 is in the path of the stud 73 carried by said cam 65. Continued clockwise turning movement of said cam 65 brings the stud 73 into engagement with the stud 52, thereby moving said member 48 counterclockwise about its pivot 47, and permits the spring 63 to restore the knee link, as shown in Fig. VI, to a position in which the axes of the stud 52, rivet pivot 56, and pivot stud 58 are in a straight line.

When the cam 65 reaches the point in its clockwise movement where its cam notch 69 is presented for engagement with the reset arm roller

15 70, said roller 70 enters the cam notch 69 and said reset arm 60 is moved clockwise about its pivot by means of the spring 75. Such clockwise movement of the reset arm 60, with the knee link members 48 and 55 in approximately a straight line position, said knee link being over center only about $\frac{1}{2}$ of an inch, as shown in Fig. VII, causes the shutter 40, with its shutter fingers 42, to be moved clockwise and raise said shutter 40 and fingers 42 to the position shown in Fig. I and in which the shutter fingers are in non-obscuring position with respect to the portions of the number wheels appearing through the apertures 13 formed in the cover plate 14.

In resetting said counter to zero, the reset cam

30 65 and crank 67 are turned clockwise in excess of 360° to effect a proper lining up of the counter wheels. Such excess clockwise movement of the cam 65 therefore carries the stud 82 beyond its tripping position, as shown in Fig. I. When

35 the reset handle 67 is released by the operator, the spring 75 effects counterclockwise compensating movement of the cam 65 as the roller 70 moves into the cam notch 69 to the position shown in Fig. I. Counterclockwise movement of the cam

40 65 causes counterclockwise movement of the stud 82 carried by said cam 65. When said stud 82, during such counterclockwise movement, comes in contact with the stud 52, the inclined cam face of said stud 82 causes said stud 82 to ride over the

45 stud 52 counterclockwise. During the riding of the stud 82 over the stud 52, said stud 82 moves outwardly in the opening 83 against the effective forces of the flat spring 80. After passing over said stud 52, the stud 82 is restored to its normal position by means of its spring 80.

It is of course to be understood that clockwise movement of the reset handle 67 through one complete revolution, as described above, contemporaneously causes the counter wheels 1 to be restored to zero position through conventional means well-known in the counter or indicating registering mechanism art.

I do not desire to limit myself to the precise details of construction and arrangement above described, as it is obvious that various modifications may be made therein without departing from the essential features of my invention, as defined in the appended claims.

I claim:

65 1. In shutter warning means for registering mechanisms which include tens transfer mechanism and a plurality of wheels carrying indicia on their faces; a shutter pivoted about the same axis as said wheels and alternately movable to 70 concealing and exposing positions in front thereof, means for resetting said wheels to zero position and including a reset cam having a notch in its periphery and a pivoted reset arm having a stud engageable in said notch when said wheels 75 are in zero position and arranged to be cammed

out of said notch upon initial resetting movement of said resetting means whereby to cause pivotal movement of said arm, a knee toggle joint link connection between said shutter and said reset arm and having a slightly over center substantially straight line position when said shutter is in exposing position, a spring continually tending to move said shutter to concealing position, and means carried by said cam for tripping said link to a broken condition at the initiation of a resetting operation and thus permit said spring to move said shutter at the initiation of a resetting operation to a concealing position.

2. In shutter warning means for registering mechanisms which include tens transfer mechanism and a plurality of wheels carrying indicia on their faces; a shutter pivoted about the same axis as said wheels and alternately movable to concealing and exposing positions in front thereof, means for resetting said wheels to zero position and including a reset cam having a notch in its periphery and a pivoted reset arm having a stud engageable in said notch when said wheels are in zero position and arranged to be cammed out of said notch upon initial resetting movement of said resetting means whereby to cause pivotal movement of said arm, a knee toggle joint link connection between said shutter and said reset arm and having a slightly over center substantially straight line position when said shutter is in exposing position, a spring continually tending to move said shutter to concealing position, means carried by said cam for tripping said link to a broken condition at the initiation of a resetting operation and thus permit said spring to move said shutter at the initiation of a resetting operation to a concealing position, and means carried by said cam for restoring said link to its substantially straight line position at the end of the resetting operation whereby to move said shutter to exposing position after the wheels have been reset to zero.

3. In shutter warning means for registering mechanisms which include tens transfer mechanism and a plurality of wheels carrying indicia on their faces; a shutter pivoted about the same axis as said wheels and alternately movable to concealing and exposing positions in front thereof, means for resetting said wheels to zero position and including a reset cam having a notch in its periphery and a pivoted reset arm having a stud engageable in said notch when said wheels are in zero position and arranged to be cammed out of said notch upon initial resetting movement of said resetting means whereby to cause pivotal movement of said arm, a knee toggle joint link connection between said shutter and said reset arm and having a slightly over center substantially straight line position when said shutter is in exposing position, a spring continually tending to move said shutter to concealing position, a first stud carried by said cam for tripping said link to a broken condition at the initiation of a resetting operation and thus permit said spring to move said shutter at the initiation of a resetting operation to a concealing position, and a second stud carried by said cam for restoring said link to its substantially straight line position at the end of the resetting operation whereby to move said shutter to exposing position after the wheels have been reset to zero.

4. In shutter warning means for registering

mechanisms which include tens transfer mechanism and a plurality of wheels carrying indicia on their faces; a shutter pivoted about the same axis as said wheels and alternately movable to concealing and exposing positions in front thereof, means for resetting said wheels to zero position and including a reset cam having a notch in its periphery and a pivoted reset arm having a stud engageable in said notch when said wheels are in zero position and arranged to be cammed out of said notch upon initial resetting movement of said resetting means whereby to cause pivotal movement of said arm, a knee toggle joint link connection between and pivotally connected at its opposite ends to said shutter and said reset arm and having a slightly over center substantially straight line position when said shutter is in exposing position, said link connection having a tripping stud adjacent one end thereof, a spring continually tending to move said shutter to concealing position, a second spring between the links of said link connection normally urging the link connection to its straight line position, a first stud carried by said cam and engageable with said tripping stud for tripping said link to a broken condition at the initiation of a resetting operation and thus permit said first mentioned spring to move said shutter at the initiation of a resetting operation to a concealing position, and a second stud carried by said cam and engageable with said tripping stud for restoring said link to its substantially straight line position at the end of the resetting operation whereby to move said shutter to exposing position after the wheels have been reset to zero.

5. In shutter warning means for registering mechanisms which include tens transfer mechanism and a plurality of wheels carrying indicia on their faces; a shutter pivoted about the same axis as said wheels and alternately movable to concealing and exposing positions in front thereof, means for resetting said wheels to zero position and including a reset cam having a notch in its periphery and a pivoted reset arm having a stud engageable in said notch when said wheels are in zero position and arranged to be cammed out of said notch upon initial resetting movement of said resetting means whereby to cause pivotal movement of said arm, said stud after said wheels have been reset to zero being again engageable in said notch and causing a limited retrograde rotation of said cam, a knee toggle joint link connection between said shutter and reset arm and having a slightly over center substantially straight line position when said shutter is in exposing position, said link connection having a tripping stud adjacent one end thereof, a spring continually tending to move said shutter to concealing position, a spring pressed stud carried by said cam and engageable with said tripping stud for tripping said link to a broken condition at the initiation of a resetting operation, and a second stud carried by said cam and engageable with said tripping stud for restoring said link to its substantially straight line position at the end of the resetting operation, said spring pressed stud having an inclined cam surface adapted to ride over said tripping stud without moving the same upon retrograde rotation of said cam.

EINAR M. ORBECK.
